UNITED STATES PATENT OFFICE.

WILLIAM GORMAN, OF NEW BRITAIN, CONNECTICUT, ASSIGNOR TO RUSSELL AND ERWIN MANUFACTURING COMPANY, OF SAME PLACE.

DESIGN FOR A SHUTTER-BAR.

Specification forming part of Design No. 5,938, dated June 18, 1872.

Specification describing a Design for a Shutter-Bar, invented by WILLIAM GORMAN, of New Britain, in the county of Hartford and State of Connecticut.

The nature of my design is fully represented in the accompanying photographic illustration, to which reference is made.

A represents the bar proper, and B the buttons and C the plates by which they are secured to a shutter. The buttons B have a small ornamental figure at the center, outside of which figure is a raised ledge in the form of a square, around which are two raised circles, as shown. The plates C are ornamented by a raised border and fancy-work. The contour

of the bar A is composed mainly of curved lines, arranged, as shown, so as to form a wing at its upper and lower edge, and thereby widen the bar. Upon the front surface of the bar is ornamental work in relief.

I claim as my invention—

1. The design for the contour of the bar proper, A, as shown in the drawing.
2. The design for a shutter-bar, as shown in the drawing.

WILLIAM GORMAN.
